UNITED STATES PATENT OFFICE.

WILLIAM H. SOLEY, OF PHILADELPHIA, PENNSYLVANIA, ASSIGNOR OF ONE-HALF TO GEORGE A. DALLETT, OF SAME PLACE, AND THOMAS H. DALLETT, OF CHEYNEY, PENNSYLVANIA, COMPOSING THE FIRM OF THOMAS H. DALLETT & COMPANY.

PNEUMATIC TOOL.

SPECIFICATION forming part of Letters Patent No. 670,646, dated March 26, 1901.

Application filed May 3, 1900. Serial No. 15,327. (No model.)

To all whom it may concern:

Be it known that I, WILLIAM H. SOLEY, a citizen of the United States, residing at Philadelphia, county of Philadelphia, and State of Pennsylvania, have invented a new and useful Improvement in Pneumatic Tools, of which the following is a full, clear, and exact description, reference being had to the accompanying drawings, which form a part of this specification.

My invention refers to that class of tools known as "pneumatic" tools, which are used for cutting, chipping, riveting, &c.

The particular purpose of my invention is to produce a tool of this class which will be of simple construction, which will enable a long stroke to be obtained, and which will reduce the vibration to a minimum.

It also consists in certain novel details of construction, all of which will more fully appear in the following specification.

In the drawings, Figure 1 is a section through the cylinder on the line 1 1 of Fig. 2. Fig. 2 is a section on the line 2 2 of Fig. 1. Fig. 3 is a section on the line 3 3 of Fig. 1. Fig. 4 is a section on the line 1 1 of Fig. 2, showing the piston ready to descend. Fig. 5 is a sectional view showing the piston in its descending position at the point the valve is shifted. Fig. 6 is a sectional view showing the piston ready to ascend. Fig. 7 is a sectional view showing the piston in its upper position ready to shift the valve.

A is the casing of the tool, which is bored out to form a chamber C, of greater and lesser diameter at different points, as shown at a a'.

B is a longitudinal passage through the casing in connection with the source of air-supply and connecting with the port b, which passes laterally through the casing to the chamber C at the lower end of the larger portion a. D is a piston in said chamber having two areas, one of substantially the size of the larger portion of the chamber and the other of the size of the smaller portion of the chamber C. The air from the air-supply passes constantly to the chamber C through the port b. There is therefore a constant air-pressure beneath the shoulder d of the piston, tending to force the piston upward in the chamber. The piston D is bored out for a distance from

the top downward, forming the valve-chamber e, in which is placed the valve E. This valve is a vertically-reciprocating valve. Extending from the lower end of this valve-chamber 55 and through the piston is the passage e', terminating in the port e². In the piston surrounding the valve is the chamber e³, which by the passage e⁴ is constantly in connection with the live air in the cylinder from port b. 60

e⁵ is a longitudinal passage in the valve E, connected with the lateral port or passage e⁶, the passage e⁵ extending from port or passage e⁶ to the upper end of valve. In the top of the piston is an orifice, in which is secured 65 the orifized nut e⁸, having the orifized projecting portion e⁹, of size sufficient to allow it to enter the orifice e⁵ of the valve. Surrounding this projecting portion e⁹ is a fiber washer-ring. The washer is of different diameters, one portion e¹⁰ overlying and being substantially of the size of the nut e⁸, so as to rest against it, and the other portion e¹¹ projecting from the portion e¹⁰ and surrounding the projecting portion e⁹, but not extending to the end thereof. The lower end of the chamber C has the annular enlarged portions a² and a³, communicating by passages 70 a⁴ and a⁵, respectively, with the atmosphere. 75

F is a passage communicating with the upper end of the valve-chamber e and extending longitudinally through the piston to the lower end thereof. A small passage e²⁰ connects the passage e⁵ and passage e'. This passage e²⁰ is of considerably less area than 80 passage e⁵.

I will now describe the operation of the tool, starting at the position shown in Fig. 4, when the piston is in position to descend. In this position air is admitted from passage B through port b, port e², and passage e' to lower side of valve E to hold it in position, so that port e⁶ registers with chamber e³, and the air in that chamber from the constant pressure-supply passes up through the passage e⁵ in the valve 90 and through the orifized nut e⁸ to the top of the piston D, the upper side of the piston being of greater area than the shoulder d, (subject to constant pressure.) The piston D and valve E move down together until the port e² 95 comes opposite the portion a² of the chamber C, the exhaust below the piston passing 100

through the ports a^4 and a^5 . When this position is reached, the valve-chamber e below the valve E will be connected with the exhaust. The air-pressure on top of the valve 5 E will then force the valve E downward, moving the port e^6 from connection with chamber e^3 , cutting off the supply of air to the top of the piston, and opening the passage F , so that during the further downward movement of 10 the piston, due to expansion of air above the piston and inertia of the piston, the air above the piston is being exhausted. This is of great importance, as the chamber a^2 may be arranged at such a position that the exhaust 15 of the air above the piston will commence at such a time that when the end of the stroke is reached substantially all the pressure above the piston is exhausted and the rebound of the piston produces, if any, but a slight shock. 20 When in the downward movement of the piston the air above the piston is exhausted, the air below the shoulder d will become effective and the piston will rise until the port e^2 registers with the constant live air in the chamber 25 C , at which time the air will pass into the passage e' , and thus to the valve-chamber e , shifting the valve, so that air will pass from the chamber e^3 through port e^6 and passage e^5 to top of piston, when the piston will again 30 descend. In order to avoid any downward movement of the valve where air is above the valve, due to the piston not fitting the chamber tightly, I provide the passage e^{20} in the valve E , which allows live air to pass from 35 passage e^5 to bottom of valve to compensate for any leakage. The construction of fiber washer e^{10} and e^{11} and sustaining it upon the nut and around the projection is of importance, as when the valve ascends the end of 40 valve strikes the piston e^{11} of washer and the washer is held firmly and from lateral spreading and maintains a constant cushion. 45 Having now fully described my invention, what I claim, and desire to protect by Letters Patent, is—
1. In a pneumatic tool, in combination, a casing provided with a chamber, a shouldered piston in said chamber, a constant source of pressure-supply in said chamber below said 50 shoulder, a valve-chamber formed in the piston, a passage from said valve-chamber through the piston to the opposite side of said shoulder, a passage from the constant air-supply to said valve-chamber and a vertically-reciprocating valve in said valve-chamber and a longitudinal passage from the lower end of said valve-chamber opening into the piston-chamber above the lower end of said piston and an exhaust-passage from the piston-chamber above its lower end.
55 2. In a pneumatic tool, in combination, a casing provided with a chamber, a shouldered piston in said chamber, a constant source of 60 air-supply to the piston-chamber, a valve-chamber formed in the piston, a passage from the lower end of said valve-chamber opening into the piston-chamber above the lower end of said piston and an exhaust-passage from the piston-chamber above its lower end.

65 pressure-supply in said chamber below said shoulder, a valve-chamber formed in the piston, a passage from the upper end of said valve-chamber, through the piston to the up-

65 pressure supply in said chamber below said shoulder, a valve-chamber formed in the piston, a passage from the upper end of said valve-chamber, through the piston to the up-

per side of said piston, a passage connecting said valve-chamber with the constant air-supply, a passage leading from the upper end of 70 said valve-chamber to the lower end of said piston, an exhaust - passage from the lower end of the piston-chamber, and a vertically-reciprocating valve in said valve-chamber, and a longitudinal passage from the lower 75 end of said valve-chamber opening into the piston-chamber above the lower end of said piston and an exhaust - passage from the piston-chamber above its lower end.

3. In a pneumatic tool, in combination, a 80
casing provided with a chamber, a shouldered
piston in said chamber, a constant source of
pressure-supply in said chamber below said
shoulder, a valve-chamber formed in the pis-
ton, a passage from the upper end of said 85
valve-chamber through the piston to the up-
per side of said piston, a passage connecting
said valve-chamber with the constant air-sup-
ply, a passage leading from the upper end of
said valve-chamber to the lower end of said 90
piston, an exhaust - passage from the lower
end of the piston-chamber, a vertically-recip-
rocating valve in said chamber, said valve
having a vertical passage open at its upper
end and terminating at its lower end in a lat- 95
eral port adapted in the reciprocation of the
valve to connect with the passage from the
constant air-supply and a longitudinal pas-
sage from the lower end of said valve-cham-
ber opening into the piston-chamber above
the lower end of said piston and an exhaust- 100
passage from the piston - chamber above its
lower end.

4. In a pneumatic tool, in combination, a casing provided with a chamber, a shouldered piston in said chamber, a constant source of pressure-supply in said chamber below said shoulder, a valve-chamber formed in the piston, a passage from the upper end of said valve-chamber through the piston to the upper side of said piston, a passage connecting said valve-chamber with the constant air-supply, a passage leading from the upper end of said valve-chamber to the lower end of said piston, an exhaust-passage from the lower end of the piston-chamber, a vertically-reciprocating valve in said chamber, said valve having a vertical passage open at its upper end and terminating at its lower end in a lateral port adapted in the reciprocation of the valve to connect it with the passage from the constant air-supply, a passage extending through the lower end of the valve to the passage in the valve. 105 110 115 120

5. In a pneumatic tool, in combination, a casing provided with a chamber, a shouldered piston in said casing, a constant source of pressure-supply in said chamber below said shoulder, a valve-chamber formed in the piston, a passage from the upper end of said valve-chamber through the piston to the upper side of said piston, a passage connecting said valve-chamber with the constant air-supply, a passage leading from the upper end

of said valve-chamber to the lower end of said piston, an exhaust-passage from the lower end of the piston-chamber, a vertically-reciprocating valve in said chamber, 5 said valve having a vertical passage open at its upper end and terminating at its lower end in a lateral port adapted in the reciprocation of the valve to connect with the passage from the constant air-supply, and a longitudinal passage from the lower end of said valve-chamber opening into the piston-chamber and an exhaust-passage from the lower portion of said piston-chamber, a passage extending through the lower end of the valve to 10 the passage in the valve.

6. In a pneumatic tool, in combination, a casing provided with a chamber, a shouldered piston in said chamber, a constant source of pressure-supply in said chamber below said shoulder, a valve-chamber formed in the piston, a passage from the upper end of said valve-chamber through the piston to the upper side of said piston, a passage connecting said valve-chamber with the constant air-supply, a passage leading from the upper end of said valve-chamber to the lower end of said piston, an exhaust-passage from the lower end of the piston-chamber, a vertically-reciprocating valve in said chamber, said valve 15 having a vertical passage open at its upper end and terminating at its lower end in a lateral port adapted in the reciprocation of the valve to connect with the passage from the constant air-supply and a longitudinal passage 20 from the lower end of said valve-chamber opening into the piston-chamber above the lower end of said piston and an exhaust-pas-

sage from the piston-chamber above its lower end, a passage extending through the lower end of the valve to the passage in the valve. 40

7. In a pneumatic tool of the character described, a piston having formed in its upper portion a valve-chamber open to the upper side of said piston, an orificed valve in said valve-chamber, a hollow projecting portion 45 from the piston in said valve-chamber, of a size adapted to enter the orifice in the valve and a fiber washer surrounding said projecting portion, to a point slightly above its end, said fiber washer being formed of a main portion resting upon the piston-head and a projecting portion of less area surrounding the projecting portion from the piston. 50

8. In a pneumatic tool of the character described, a piston having formed in its upper portion a valve-chamber open to the upper side of said piston, an orificed valve in said chamber, an orificed nut secured in the orifice in the piston having an orificed projection of size adapted to enter the orifice in the valve, 55 and a fiber washer surrounding said projecting portion to a point slightly above its end, said fiber washer being formed of a main portion resting upon the main portion of the nut and a projecting portion of less area surrounding the projecting portion from the nut. 60

In testimony of which invention I have hereunto set my hand, at Philadelphia, Pennsylvania, on this 16th day of April, 1900.

WILLIAM H. SOLEY.
